UNITED STATES PATENT OFFICE

FRANK ALBACH, OF ST. LOUIS, MISSOURI, ASSIGNOR TO FRED MEDART MANUFACTURING COMPANY, OF ST. LOUIS, MISSOURI, A CORPORATION OF MISSOURI

STRADDLE STAND OR SUPPORT

Application filed August 10, 1928. Serial No. 298,795.

This invention relates to that class of straddle stands or supports adapted to afford overhead support for playground exercising appliances, such as swings, horizontal bars, etc., and has for its object.

To provide a structural combination and arrangement of upright side rails horizontal tie rails, horizontal stringer or rail and vertical bracing rails in a stand or support of the type above referred to, by means of which a light strong and rigid structure, capable of ready removal from place to place is provided.

To provide a ready and effective construction and combination of parts in the described type of stands or supports whereby a horizontal bar for athletic exercise is adjustably supported at the desired distance above the ground or floor, all as will hereinafter more fully appear.

In the accompanying drawing:

Fig. 1, is a perspective view of a stand or support embodying this invention.

Fig. 2, is a detail front elevation illustrating the bracing arrangement between the top horizontal stringer and the supporting side upright members of the structure.

Fig. 3, is a fragmentary side elevation of the separable connection between the horizontal exercising bar and a vertical rail of the structure.

Fig. 4, is a detail front elevation of the same.

Like reference numerals indicate like parts in the different views.

In this invention the general arrangement of parts of the stand or support is that of the ordinary straddle type and in which a pair of side supports 1 of an A-form carry at their upper ends a horizontally arranged transverse stringer or rail 2 from which are suspended a swing 3, a trapeze 4 and other like appliances as used in playground exercises.

Such appliances have detachable attachment to the stringer or rail 2, so as to be capable of removal and replacement one for the other as required in the use of any particular appliance, and as usual in this type of playground apparatus. In the structure shown in Fig. 1, each of the side supports 1 com-

prises a pair of rails or uprights which meet in adjacent relation at top and are attached to the respective faces of the aforesaid stringer or rail 2, by bolts or like fastening means passing through the respective parts, 55 and in a manner which will cause a convergence of the supports 2 towards each other at top, while their lower and spread apart ends of said supports are connected together in a spread apart relation by front and rear rails 60 bottom rails or braces 5, with a firm connection between the parts effected by screw bolts or like fastening means supplemented by diagonal bracing rails 6 secured in angular relation to the respective rails of the supports 65 1 and front and rear rails or braces 5, as shown in Fig. 1.

At the midheight of each upright support 1 a horizontal tie rail 7 is fixedly secured by screw bolts or like fastening means to secure 70 the pair of rails comprising each support 1 in proper spread apart relation. In this construction each of the tie rails 7 also provides abutments for the lower ends of the herein-after described pair of vertically arranged 75 bars or rails 8 by means of which a horizontal exercising bar 9 is supported at its ends in a vertically adjustable manner.

A material feature of this invention in connection with a frame or stand as above described involves in combination therewith the formation of extensions 2' of the respective ends of the overhead stringer or rail 2 a distance beyond the attachment between said stringer and the side support 1, and the aforesaid pair of vertical bars 8, which extend between the ends 2' of the stringer 2 and the aforesaid tie rails 7 of the side supports 1. 85

With such formation and arrangement of the parts a substantial trussing of the respective upper corners of the stand or support is attained and which is adapted to withstand the usual heavy stresses that are imposed in actual use.

In the above described construction the vertical bars 8 have a spaced relation of an extent equal to the width of the structure and that of the main central portion of the round horizontal exercising bar 9, heretofore referred to, and said vertical bars 8 are formed 95 100

with counterpart series of socket orifices 10 in vertically spaced relation, with the upper portion of each of said socket orifices of a circular formation of a size corresponding 5 with the diameter of the horizontal bar 9 in order that said horizontal bar may be passed therethrough in an endwise manner, while the lower portion 10' of each of said socket orifices have a reduced width and are adapted 10 to receive a correspondingly reduced end 9' of the horizontal bar 9 to hold the same from both turning and endwise movements in actual use.

I claim as my invention:

15 1. A stand for exercising appliances of the type described, comprising a horizontal top stringer, a pair of side supports in sloping relation and secured at the upper end to the top stringer at a distance from the ends 20 thereof, the lower ends of the supports having a greater spread relation than the length of the top stringer, tie rails secured to said supports near their mid-height, and a pair of vertical bars secured at their upper ends 25 to the respective outer ends of the aforesaid top stringer and at their lower ends to the tie rails aforesaid, said vertical bars having a spaced parallel relation adapting them to provide vertically adjustable means of attachment for exercising and like appliances. 30

2. A stand of the straddle type, comprising a horizontal top stringer affording means for attachment for swinging exercising appliances, a pair of side supports converging 35 together at top, each support comprising a pair of rails which incline towards each other at top and secured at their upper ends to the aforesaid horizontal stringer, a tie rail secured to said pair of rails at their mid-40 height, the top stringer having end extensions beyond the points of attachment of the side supports, and vertical bars attached to said end extensions of said stringer and said tie rails to provide strengthening trusses for the 45 upper corners of the stand, each vertical bar aforesaid having a vertical series of socket orifices for receiving and supporting the ends of a horizontal exercising bar.

3. A stand of the straddle type, comprising 50 a horizontal top stringer affording means for attachment for swinging exercising appliances, a pair of side supports converging together at top, each support comprising a pair of rails which incline towards each 55 other at top and secured at their upper ends to the aforesaid horizontal stringer, a tie rail secured to said pair of rails at their mid-height, the top stringer having end extensions beyond the points of attachment of 60 the side supports, and vertical bars attached to said end extensions of said stringer and said tie rails, to provide strengthening trusses for the upper corners of the stand, each vertical bar aforesaid having a vertical 65 series of socket orifices for receiving and sup-

porting the ends of a horizontal exercising bar, and each of said socket orifices having a circular upper portion corresponding with the diameter of said exercising bar and a lower narrow portion adapted to receive a 70 correspondingly reduced end of said bar.

In testimony whereof I hereunto affix my signature.

FRANK ALBACH.
